UNITED STATES PATENT OFFICE.

CHARLES ALGERNON PARSONS, JESSEL ROSEN, ARTHUR WALLACE GREY, AND BEN-JAMIN BLAIR, OF NEWCASTLE-ON-TYNE, ENGLAND; SAID ROSEN, SAID GREY, AND SAID BLAIR ASSIGNORS TO SAID PARSONS.

ELECTRICAL CONDUCTOR.

Application filed November 8, 1925, Serial No. 68,037, and in Great Britain December 29, 1924.

The present invention relates to electrical conductors and particularly to those of a flat elongated form suitable for the slot windings of dynamo-electric machines.

- 5 With a view to eliminating eddy-current losses in such conductors, they have been commonly built up of a large number of comparatively small helically-disposed insulated strands. In order to make the best 10 possible use of the space available for such conductors, the insulation on the individual strands has necessarily to be very thin and owing to the danger of adjacent wires over-riding, and to the pressure to which the conductors are subjected in the course of manufacture it is found in certain circumstances that the insulation breaks down, thereby 15 causing contact between adjacent conductors and a consequent loss of efficiency.
- 20 The object of the present invention is to overcome difficulties of the nature pointed out above.

With such an object:—

25 The present invention consists in the features of novelty hereinafter fully described and pointed out in the claims.

Referring to the accompanying diagrammatic drawings:—

30 Figure 1 shows a side elevation of one form of machine according to the present invention in which insulating material is introduced by way of a hollow core,

Figure 2 being a cross section on the line 2—2 of Figure 1, looking in the direction of 35 the arrows;

Figure 3 shows a perspective view to an enlarged scale of part of the hollow core with tongue for securing it in place;

40 Figure 4 shows a side elevation of a modified form of machine having a solid dummy core, and

Figure 5 a detail of another modification, in which two strips of insulation are used, while finally

45 Figure 6 shows a perspective view to an enlarged scale of a flat elongated conductor with interposed insulation according to the present invention,

50 Figure 7 showing a cross section also to an enlarged scale of a conductor having additional insulated layers.

The same reference symbols are used in

the different drawings to denote corresponding parts.

In carrying the invention into effect according to the illustrative form shown in Figures 1 and 2, a modification of the machine described in the specification of British Patent No. 16,620 of 1908, of which one of the present applicants was a co-grantee, 55 may be adopted. Thus, while maintaining all the essential parts of the machine therein described, including the revolably-mounted reels, *a*, carrying the individual strands, *b*, the die-plate, *c*, throat-piece, *d*, adjustable 60 rolls, *e*, and so forth, the dummy core, *f*, for the manufacture of the conductor of an elongated or flat cross section, as shown for example in Figure 6, is modified by being constructed of a hollow form and insulation, 65 *h*, of a suitable deformable material in strip or tape form is passed through the hollow core into the centre of the helically-disposed strands, *b*, the whole being then subjected to pressure by the adjustable rolls, *e*. 70

In Figure 1, the end of the dummy core from which the insulation emerges is indicated at *f'*.

The dummy core, *f*, may be conveniently constructed as shown in Figure 3, i. e., with 80 a tubular portion, *f*² and an integral tongue, *f*³, for attachment to the stationary mandrel, *g*.

With suitable material it is found in practice that the insulation so treated oozes up 85 between the strands themselves and fills the interstices between them. Under the proper conditions this action may be so effective that the copper strands themselves as drawn from their reels may be uninsulated.

According to the nature of the material used, the insulation so added may deform to a sufficient extent only partially to fill the interstices as seen in Figure 6, but the action aimed at in every case is to add insulation 95 with the minimum increase in the dimensions of the conductor as a whole.

In a modified form of the machine described above, (see Figure 4) the dummy core, *h*, may be made of flat form as before 100 and the insulating strip, *h*, fed over its surface to the interior of the stranded conductor, as shown.

By treating the first two layers of the

stranded cable, e. g. the two layers shown in Figure 6, as a core for additional layers, insulation can be inserted in this manner beneath each additional layer as it is helically laid in place, so as to build up a conductor, for example, as shown in Figure 7, the preferable arrangement in such a case being that two strips of insulation are simultaneously inserted one on each side of the basic strand-
ed core. Thus as shown in Figure 5, the two strips of insulation are indicated at *h*, *h'*, and the basic core which takes the place of the original dummy core, at *m*.

The function of such a core in each case is to determine the shape of the conductor and to act as a member resistant to the stresses imposed by the helical laying of the wire strands, the insulating material owing to its deformability or plasticity being in-
capable of performing such functions.

It will be seen that the processes of manufacture according to the present invention are continuous, the operations of helical stranding and introduction of insulating ma-
terial proceeding simultaneously.

The insulating material may be of any degree of deformability, ranging in different cases from the micaceous or fibrous to the plastic or even liquid state, pressure being used if desirable.

An electric conductor manufactured according to the fundamental principle of the present invention is highly efficient as regards the insulating from one another of the individual strands while at the same time the latter receive additional mechanical protection.

Although the invention has been specially devised for the manufacture of electrical conductors of the elongated cross section described, it is nevertheless applicable to other forms of cross section while in addition the details of the processes and machines described can be varied without de-
parting from the underlying principle of the invention.

Having now described our invention, what we claim as new and desire to secure by Letters Patent, is:—

50. 1. A process of manufacturing electrical conductors having a plurality of faces, consisting in juxtaposing deformable insulation in layer form in longitudinal relation to a resistant shape-determining member having faces similarly disposed to those of the finished conductor; helically laying around said shape-determining member and said juxtaposed insulation a series of wire strands; and separating said shape-determining member and said strands so laid.

60. 2. A process of manufacturing electrical conductors having a plurality of faces, consisting in juxtaposing plastic insulation in layer form in longitudinal relation to a re-
sistant shape-determining member having

faces similarly disposed to those of the finished conductor, helically laying around said shape-determining member and said juxtaposed insulation a series of wire strands and subsequently applying external pressure 70 to locate finally said series of wire strands and to force said plastic insulation into the interstices therebetween.

3. A process of manufacturing electrical conductors having a plurality of faces con-
sisting in juxtaposing deformable insulation 75 in strip form in longitudinal relation to a resistant shape-determining member having faces similarly disposed to those of the finished conductor; helically laying around said shape-determining member and said juxtaposed insulation a series of wire strands; and separating said shape-deter-
mining member and said strands so laid.

4. A process of manufacturing electrical 85 conductors having a plurality of faces, con-
sisting in progressively juxtaposing deformable insulation in strip form in longitudinal relation to a resistant shape-determining member having as many faces as the finished 90 conductor; helically laying around said shape-determining member and said juxtaposed insulation a series of wire strands; and separating said shape-determining mem-
ber and said strands so laid.

5. A process of manufacturing electrical 95 conductors having a plurality of faces, con-
sisting in simultaneously juxtaposing strips of deformable insulation in longitudinal re-
lation to a resistant shape-determining mem-
ber having as many faces as the finished 100 conductor; helically laying around said shape-determining member and said juxtaposed insulation a series of wire strands; and separating said shape-determining mem-
ber and said strands so laid.

6. A process of manufacturing electrical 105 conductors having an oblong cross-section con-
sisting in sliding insulation material lon-
gitudinally along a resistant shape-deter-
mining member likewise having an oblong 110 cross section; helically laying around said shape-determining member and said juxtaposed insulation a series of wire strands; and separating said shape-determining mem-
ber and said strands so laid.

7. An additional step of the process 115 claimed in claim 6, according to which the conductor manufactured as set forth in claim 6, itself forms a resistant shape-de-
termining member for the super-position thereon of additional separate strips of in-
sulation juxtaposed longitudinally one strip 120 on each wide face of said member and an ad-
ditional helical series of wire strands laid therearound.

8. A process of manufacturing electrical 125 conductors as claimed in claim 6, in which the insulation is of a plastic nature and in which the electrical conductor manufactured 130

as set forth in said claim 6 is submitted to sufficient pressure finally to locate said helically-laid wire strands and to cause said plastic material to fill the interstices therebetween.

9. A process of manufacturing electrical conductors as claimed in claim 6, according to which the resistant shape-determining

member is hollow and the insulation material is slid therethrough.

In testimony whereof we have signed our names to this specification.
